CLAIM

The ornamental design for an intelligent digital fracture fixed splint, as shown and described.

DESCRIPTION

FIG. 1 is a top view of an intelligent digital fracture fixed splint showing my new design;

FIG. 2 is a bottom view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a perspective view thereof.
